TUBE EXPANDING TOOL

Marcus Tomarin, Cincinnati, Ohio

Application June 23, 1950, Serial No. 169,908

3 Claims. (Cl. 153—80.5)

1

This invention relates to a tube expander, and more particularly to a compact manually operable device for expanding or flaring the ends of lengths of tubing.

An object of the invention is to provide a simple, inexpensive, yet highly efficient tube expander which is so constructed and arranged as to facilitate its use in "on location" jobs, thereby enabling the plumber to use it in such heretofore inaccessible locations as between wall studding, floor joists, and the like.

Another object of the invention is to provide a tube expander which includes an expanding die member which is constructed in such a manner as to reduce to an absolute minimum the frictional forces encountered incident to a tube expanding operation, thereby enabling the device to effectively expand the ends of tubes incident to manual operation of the tool.

A further object of the invention is to provide a tube expander having a tube expanding die which is particularly adapted to provide an integral, elongated, enlarged sleeve on the end of a length of tubing, wherein the inside diameter of said sleeve is of a dimension at least equal to the nominal outside diameter of the pipe before being expanded.

Still a further object of the invention is to provide a tube expander having the hereinabove described characteristics and which is adapted to accommodate a variety of tube sizes, thereby greatly enhancing its utility.

These and other objects are attained by the means described herein and as disclosed in the accompanying drawings, in which

Fig. 1 is a top plan view of a tube expander embodying the teachings of the present invention.

Fig. 2 is a side elevation of the device of Fig. 1.

Fig. 3 is a sectional view taken on line 3—3 of Fig. 2.

Figs. 4 and 5 are top views of two different sizes of tube gripping elements which comprise a detail of the invention.

Figs. 6, 7 and 8 are views, partly in section, illustrating the sequential steps followed in the process of expanding the end of a length of tubing with the tool of Fig. 1.

Fig. 9 is a sectional view illustrating a typical connection made with tubing, the end of one of which of said pieces has been provided with a sleeve formed by my tool.

With reference now to Fig. 1, the numerals 10 and 12 denote, generally, a pair of jaw members which, as best disclosed in Fig. 3, are provided

2

with a recessed portion 14 with which the respective halves 16 and 18 of a tube gripping element are received. Jaw 10 may be releasably and hingedly secured to jaw 12 by means of an eye-bolt 20, the loop 22 of which engages pin 24 which is secured to and carried by jaw 10. A wing nut 26 engages the free outer end of bolt 20 the shank of which extends through axial bore 28 in jaw 12, as illustrated.

10 The forward ends of the jaw elements are likewise releasably secured together by means of an eye-bolt 30 loop 32 of which engages pin 34 of jaw 10.

15 With reference now to Fig. 2, it will be observed that the forward end of jaw 12 is provided with a slotted portion 36 within which the shank of eye-bolt 30 may be received when said bolt is pivoted about pin 34. A wing nut 38 enables an operator to draw jaw sections 10 and 12 together for securely, though releasably, clamping the end portion of a length of tubing 40 (see 6, 7 and 8) to and between clamping elements 16 and 18.

20 A fulcrum post 42 is rigidly secured to jaw 12 adjacent its forward end, and a second or guide post 44 is likewise rigidly secured to the jaw adjacent its rearward portion. The upper portion of post 42 is bifurcated for providing a pair of laterally spaced ears 46 between which the forward end of an actuator lever 48 is pivotally secured as by means of bolt 50. The upper portion of post 44 is likewise bifurcated for providing a pair of laterally spaced lever guiding ears 52, between which lever 48 is slidably receivable.

25 As best disclosed in Fig. 1, the rearward portion of lever 48 terminates in a socket portion 54 which is constructed and arranged in such a manner as to releasably receive a suitable length of pipe or other handle member inserted therein for increasing the leverage of the lever.

30 Jaw 12 has a lever 56 formed integrally therewith, the same being shown in the form of a socket dimensioned to releasably receive the end of a length of pipe or handle member, not illustrated.

35 A stem 61 is pivotally secured to lever 48 as at 62, it being noted that the upper end of the stem 61 is provided with a pair of laterally spaced members 64 which straddle opposite faces of lever 48. Rigidly secured on the lower end of the stem 61 is a die 60 which is substantially spherical throughout an area substantially greater than a hemisphere.

40 In the preferred embodiment of the invention, the diameter of the rounded or spherical por-

tion of the die 60 is of a dimension approximating the nominal outer diameter of a length of tubing 40, the free outer end of which is to be provided with an elongated, tube-receptive sleeve.

With particular reference now to Figs. 6, 7 and 8, it will be observed that die 60 will be disposed in substantial axial alignment with tubing 40 which has previously been securely clamped between holding elements 16 and 18 for disposing a length of tubing above upper face 70 of the holding members 16 and 18. As a downward force is applied to die 60, it will be forced into tube 40 for engaging the inner face of the tubing wall whereby the free outer end of said tubing will be flared outwardly as at 72. Further downward movement of die 60 will introduce it into tubing 40 by a dimension greater than the radius of the spherical die head, at which time, see Fig. 8, those portions of the tubing which have been expanded by a maximum dimension, denoted by the numeral 74, equal to the diameter of the spherical die head, will thereafter be freed of further contact with die 60 incident to its further introduction into tubing 40. In this manner I have effectively and efficiently eliminated those frictional forces which would otherwise be present and which would resist further introduction of the die head into tubing 40.

The amount by which die 60 may be thus introduced into the tubing will be determined by upper face 70 of holding members 16 and 18.

From the foregoing, it will be apparent that I have thus provided the end of tubing 40 with an integral elongated sleeve portion 74 which, as clearly disclosed in Fig. 9, is so proportioned as to snugly receive the outer end of a length of tubing 76 having a nominal outside diameter equal to that of tubing 40. It will likewise be noted that if tubing 40 and 76 are similar, no obstruction will occur in the inside of the tubes which will diminish the flow of fluid therethrough, since the inside diameter of tubing 76 has not been reduced in size, but will remain at all times equal to the inside diameter of tubing 40.

It should be understood that various sized tubing may be accommodated merely by utilizing holding members 16 and 18 having various sized complementary tube gripping apertures 80 and 82, as illustrated in Figs. 4 and 5.

It will likewise be noted that a different die element 60 will be utilized for different sized tubing.

In operation eye bolts 20 and 30 are loosened by an amount sufficient to enable jaw elements 10 and 12 to be laterally separated by an amount sufficient to enable the insertion of the desired set of holding members 16 and 18, after which nut 26 may be drawn up for drawing eye-bolt 20 through bore 28 of jaw 12, thereby hingedly interconnecting jaws 10 and 12 as at 24. After the end of a length of tubing has been inserted upwardly through the aperture defined by the complementary portions of holding members 16 and 18, jaw 10 may be swung toward jaw 12 after which eye-bolt 30 is seated in slot 36 of jaw 12, after which the jaws may be snugly drawn together for securely anchoring the tubing thereto incident to manipulation of clamping element 38.

Preferably a reinforcing member 90 is provided in spanning relationship with posts 42 and 44, thereby enhancing the rigidity of the structure.

With particular reference now to Figs. 4-8,

it will be observed that the upper face 70 of the tube gripping elements 16 and 18 have been provided with a recess or chamfer denoted generally by the numeral 66, the radius of which is, in the preferred embodiment of the invention, equal to the radius of spherical die head 60 plus the thickness of the wall tubing. The purpose of this chamfer is to provide an abutment complementary to die 60 against which the outer wall of the tubing being expanded, adjacent the lower end of sleeve 74 may abut whereby to effectively preclude the possibility of cracking or undue weakening of the tube at the juncture of the sleeve therewith.

15 It will be observed that my die 60 may be considered as comprising an integrally formed unitary spherical pilot and sizing portion, wherein the pilot portion may be considered as that part of portion of spherical die member 60 in contact with the inner wall of flared portion 72 of tube 40, see Fig. 7. The sizing portion of die 60 may be considered as the maximum diameter thereof, which portion determines the inside diameter of sleeve 74.

20 From the foregoing it will be noted that I have provided a tube expanding tool which is easy to operate, which is adaptable to various sized tubing and which though lightweight and easily portable is nevertheless sturdy and quite rugged.

25 It should be understood that various changes and modifications may be made in the structural details of the device, within the scope of the appended claims, without departing from the spirit of the invention.

30 What is claimed is:

1. A portable manually operable tube expanding tool including a pair of elongated clamping members having opposed recesses intermediate the ends thereof, complementary sections of a tube gripping element to removably fit into said recesses for supporting a tube to be expanded, separate means at opposite ends of the clamping members for releasably securing the same together and for tightening the clamping members onto a tube received between the sections of said tube gripping element, a fulcrum post integral with one end portion of one of the clamping members, an actuator lever pivotally connected at one end to the fulcrum post for movement in only a single plane toward and from the clamping members, a stem pivotally connected at one end to the actuator lever intermediate the ends thereof and extending therefrom toward the clamping members, a spherical die rigidly secured to the outer end of said stem, a second lever rigidly secured to that one of the clamping members with which said fulcrum post is integrally formed, said second lever extending longitudinally in the plane of movement of the actuating lever from the opposite end of the clamping member on which the fulcrum post is located, said spherical die being insertable into the free outer end of a tube supported between the clamping members incident to relative movement of the actuating lever and second lever toward one another for forcing the spherical die a substantial distance into the tube for expanding that portion of the tube which projects from said tube gripping element toward the spherical die to form an elongated tubular sleeve portion.

2. A portable manually operable tube expanding tool of the construction defined in claim 1 and which has a guide post for the actuating lever formed integral with the clamping member with which the fulcrum post is integrally

formed and which is located on the opposite end portion of said clamping member from that end portion on which the fulcrum post is located, the upper part of the guide post being bifurcated to provide a pair of laterally spaced sections between which the forward part of the actuating lever is slidably received.

3. A portable manually operable tube expanding tool of the construction defined in claim 2 and which has a reinforcing member spanning the fulcrum post and guide post that are integral with one of the clamping members and is rigidly secured at opposite ends to the fulcrum post and guide post, respectively, intermediate the ends of the same.
